UNITED STATES PATENT OFFICE.

WARREN JOSEPH DOBSON, OF BUFORD, GEORGIA.

WAX-THREAD SEWING-MACHINE.

SPECIFICATION forming part of Letters Patent No. 738,011, dated September 1, 1903.

Application filed January 28, 1903. Serial No. 140,949. (No model.)

To all whom it may concern:

Be it known that I, WARREN JOSEPH DOBSON, a citizen of the United States, residing at Buford, in the county of Gwinnett and State of Georgia, have invented certain new and useful Improvements in Sewing-Machines; and I do hereby declare the following to be a full, clear, and exact description of the invention, such as will enable others skilled in the art to which it appertains to make and use the same.

My invention relates to improvements in sewing-machines, and it relates more especially to that class of sewing-machines called "wax-thread" sewing-machines intended for use in sewing leather or heavy material.

My invention will be understood by reference to the accompanying drawings, in which the same parts are indicated by the same letters throughout the several views.

Figure 1 represents a section through the frame of the machine, showing the working parts in elevation. Fig. 2 is a plan view of the device shown in Fig. 1. Fig. 3 is an end view as seen from the left of Figs. 1 and 2. Fig. 4 represents a section on the line 4 4 of Fig. 1 looking in the direction of the arrows. Fig. 4^a represents a detail showing the guide for the cam-rod for operating the shuttle. Fig. 5 represents a section on the line 5 5 of Fig. 1 looking in the direction of the arrows. Fig. 6 represents a detail showing the shuttle-holder. Fig. 7 is a sectional elevation through the head of the machine. Fig. 8 is a section along the line 8 8 of Fig. 7 and looking in the direction of the arrows. Fig. 9 is an end view showing shuttle and needle in dotted lines. Fig. 10 represents a section on the line 10 10 of Fig. 9 and looking in the direction of the arrows. Fig. 11 is a side elevation of the shuttle. Fig. 12 is an inverted plan view of the same. Fig. 13 is a top view of the same; and Fig. 14 is a diagram showing the coaction of the needle, looper, shuttle, and casting off.

A represents a frame or casing in which the parts are mounted.

B represents a main shaft which is driven by any suitable source of power—as, for instance, the pulley B⁰.

C represents the connecting-rod, connecting the crank of the main shaft to the crank D

on the needle-operating shaft D'. This shaft D' carries the crank D², connected by the link E and pin E' to the needle-bar F, carrying the needle f. This needle-bar travels in a guideway in the crank F' on the feed-shaft F², which shaft is rocked by means of the pin g (see Fig. 5) on the link G, which is connected to the crank D³ on the needle-shaft D', and thus the needle is rocked, causing it to feed the material. The length of the stitch is varied by providing slots g' and f³ in the link G and the crank F³ and by adjusting the position of the nut h' on the screw H, 65 which is pivoted by the pin h in the slot g'. By adjusting this nut h' the length of the stitch may be varied within predetermined limits. The thread is swung into the path of the needle by means of the looper K, which is mounted on the rock-shaft K'. This shaft carries a crank k, connected to the sliding bar K², which slides in the guide a. This bar K² carries a roller k², which engages in the cam-groove b and the disk B', fast to the main shaft B. As this disk rotates, the shaft K' will be rocked, and the thread will be alternately swung into and out of the line of travel of the needle. This disk B' carries a lug b', which intermittently strikes the lever L, causing the roller L' to bind the thread in the guide a⁰. (See Fig. 7.) This lever L is pivoted to the frame A, as at a'. The thread is roved through the eye n of the take-up N, which is pivoted to the lever N', pivoted in 85 the frame, as at n, and having its opposite end drawn upward by a spring N². This lever N' will be caused, by weight of the bar N and the action of the spring N², to bear on the cam B⁵, which is fast to the main shaft B, 90 and thus the intermittent action of the take-up is caused by the rotation of said shaft.

M represents an eccentric-rod connected by the eccentric-strap M' to the eccentric B² on the main shaft B. This rod is pivoted, as at m', to the stem M², carrying the awl m², and thus reciprocal motion is imparted to the awl when the main shaft revolves. The co-operation of the awl and the needle is well known in the art and need not be further described. 100

The sewing-thread leaves the spool A' (see Fig. 1) and passes through the wax-cup A² and then through suitable guides, including the opening a⁰, the eye of the take-up, and

the barb of the needle, and is dragged through the leather in the manner well known to the art.

The machine, as already described, would 5 operate as a chain-stitch machine; but in order to provide for its use either as a chain-stitch or as a lock-stitch machine I provide the shuttle and the mechanism for operating the same and means for throwing said mechanism out of operation, that will now be described.

B^3 represents a disk on the main shaft B , having a cam-groove b^3 , engaging the roller p on the connecting-rod P , which rod passes 15 through the guide A^4 , to be hereinafter more fully described, and is pivoted to the crank p' on the shuttle-shaft P' , carrying the shuttle-holder Q . This shuttle-holder has lugs q and q' , (see Fig. 6,) engaging recesses r and r' , 20 (see Figs. 11 and 12,) in the shuttle R . The shuttle is curved, as shown, and travels in an arc-shaped raceway in the frame. By proper adjustments the shuttle is caused to pass through the loop-thread above the needle 25 when the parts are in the position shown in Fig. 14, and to remove the thread from the needle I provide a curved heel or cast-off R' on the shuttle, which presses the thread out of engagement with the barb of the needle 30 when the shuttle passes through the loop, thus leaving the needle perfectly free of the thread and ready to go back through the material being sewed to make another stitch. With this mechanism for operating the shuttle the machine will operate as an ordinary 35 lock-stitch machine; but in order to throw the shuttle out of operation when desired and have the machine operate as a chain-stitch machine I provide the opening A^0 , closed 40 by a suitable door in the casing at or near the guide A^4 . By opening this door and springing the head of the rod P back to clear the roller p from the cam-groove b^3 , drawing the rod back in the elongated guideway a^4 of 45 the guide A^4 , and then swinging the head of the rod to the dotted position in the side of the recess a^5 , as shown in Fig. 4^a, the shuttle-operating mechanism will be thrown out of operation and will not operate until the roller 50 p is restored to the initial position in engagement with the cam-groove b^3 . Thus it will be seen that I provide mechanism by means of which the shuttle may be readily thrown out of or into action, and thus the machine 55 may be converted from a chain-stitch to a lock-stitch, or vice versa, at will.

u represents the presser-foot, which is moved up and down by means of the bar U and the hook U' , engaging the cam B^4 on the 60 main shaft B . This bar U carries the pin u' , which engages the spring V , (see Fig. 7,) the said spring tending to press the presser-foot

firmly on the material being sewed, except when it is lifted by the cam B^4 .

It will be obvious that various modifications in the herein-described apparatus might be made which could be used without departing from the spirit of my invention.

Having thus described my invention, what I claim, and desire to secure by Letters Patent of the United States, is—

1. In a sewing-machine, the combination with a continuously-operated looper, and a barbed needle and means for operating the same, of a shuttle, and mechanism for operating the same, and means for throwing said mechanism into or out of operation when desired, whereby a lock-stitch or a chain-stitch may be made at the will of the operator, substantially as described. 75

2. In a sewing-machine, the combination with a continuously-operated looper, and a barbed needle, and means for reciprocating the same, of a shuttle, a rock-shaft vibrating said shuttle, a main driving-shaft, a cam carried by the main shaft, and a connecting-rod adapted to be thrown into and out of engagement with said cam when desired, and connecting said cam and said rock-shaft, whereby a lock-stitch or a chain-stitch may be 85 made at the will of the operator, substantially as and for the purposes described.

3. In a sewing-machine, the combination with a continuously-operated looper, and a barbed needle and means for operating the same, a shuttle having a curved lug or cast-off projecting from the base thereof, and adapted to cast the thread off of the needle, mechanism for vibrating said shuttle, and means for throwing said mechanism into or out of operation when desired, whereby a lock-stitch or a chain-stitch may be made at 95 the will of the operator, substantially as described. 100

4. In a sewing-machine, the combination with a continuously-operated looper, and a barbed needle, and means for reciprocating the same, and for simultaneously feeding the material, of a shuttle having a curved lug or cast-off projecting from the base thereof, and adapted to cast the thread off of the needle, mechanism for vibrating said shuttle, and means for throwing said mechanism into or out of operation when desired, whereby a lock-stitch or a chain-stitch may be made at 115 the will of the operator, substantially as described. 110

In testimony whereof I affix my signature in presence of two witnesses.

WARREN JOSEPH DOBSON.
